UNITED STATES PATENT OFFICE.

RYUJI SATO AND CHIYOSABURO MATSUI, OF NEW YORK, N. Y.

ROWING RACE.

1,425,058.

Specification of Letters Patent.

Patented Aug. 8, 1922.

Application filed January 15, 1921. Serial No. 437,445.

To all whom it may concern:

Be it known that we, RYUJI SATO and CHIYOSABURO MATSUI, subjects of the Emperor of Japan, residing at New York city, respectively, in the county of New York, and State of New York, have invented new and useful Improvements in Rowing Races, of which the following is a specification.

10 This invention relates to rowing races or games for use in amusement parks, and one of the objects is to provide a device of this nature with improved operating means.

Another object is to provide automatic 15 throw-off mechanism for the operating means.

Another object is to provide means for giving a life-like simulation of rowing.

Another object is to provide means for 20 lifting and lowering the oars.

With these and incidental objects in view which will be more apparent as the specification proceeds, the invention consists of certain novel construction and combination 25 and arrangements of parts, the essential features of which are hereinafter fully described and claimed and illustrated in the accompanying drawing, in which:

Figure 1 is a perspective view of our improved boat race.

Figure 2 is a vertical sectional view on line 2--2 of Figure 1.

Figure 3 is an enlarged detail perspective view of the oar controlling cams.

35 Like characters of reference refer to like parts in all views.

Referring to the drawing in detail, 10 represents a tank which may be of any suitable size, shape and material and is water 40 tight so that the boats hereinafter described may appear to be floating therein.

In the drawings only a single boat and control are shown, but it is to be understood that any number may be used and that 45 each will be a duplication of the same shown and described.

Mounted on the bottom of the tank 10 are rails 11 which are preferably of channel bar with the channels facing each other.

50 In these channels ride wheels 12 of a carriage 13 having at its top a block 14 shaped to represent a racing boat. A line 15 has one end secured to a spring roller 16 and its other end secured to the boat 14 so as to 55 normally draw said boat against the end of the tank. A spring 17 connects a line 18

with the other end of the boat 14, said line 18 being operable by means hereinafter described, to effect movement of said boat against the tendency of said spring roller. 60

A slide member 19 is mounted to reciprocate longitudinally in said boat body, and is connected pivotally to one end of a link 20 having its other end eccentrically pivoted to the end of a drum or double pulley 65 21. Lines 22 and 23 are secured to the upper and lower portions of drum 21 and have their other ends secured to opposite ends of the tank 10. Rising from slide 19 are a plurality of figures 24 representing 70 the body portions of men provided with arms jointed at 26 and having oars 27 secured to the hand portions. These oars are swiveled in brackets 28. It will readily be seen that as the boat is drawn across the 75 tank, the figures 24 will draw the oars back and forth.

In order to make the oars dip into the water and then rise out of the water, a member 29 is secured to the edge of the boat 80 and comprises an upper cam surface 30 and a lower cam 31. A pin 32 has a finger 33 which bears upon the cams riding up 30 and being then forced down by 31 during the back and forth stroke of the oars so as 85 to cause them to dip into the water in one direction and rise above it in the other. The cam 30 has a slot 30* cut in its outer edge and of sufficient size to permit the free passage of pin 33, and cam 31 terminates 90 short of the vertical plane of slot 30*. As the finger 33 rides up the cam 30 the oars are dipped into the water. As the finger 33 passes the upper end of cam 30, the buoyancy of the oar raises the outer end of the 95 oar, lowering finger 33 into active relation with cam 31. On the return stroke, cam 31 presses element 33 down lifting the blade of the oar above the water. When finger 33 completely traverses cam 31, the weight of 100 the blade and leverage of parts causes finger 33 to move up through slot 30* to the initial position. Figure 3 shows the pin just escaping from cam 31.

Hingedly secured to the bottom of the 105 tank is a plurality of supports 34 which carry buoys or other obstructions 35. Springs 36 tend constantly to move members 34 and 35 against the bottom of the tank and lines 37 are connected at one end to respective 110 members 34 and at the other to respective cranks on a crank shaft 38 which may be

- manually operated by handle 39 or automatically operated by a motor 40 and in either case effects the oscillating of members 34 into and out of the path of the boat 14.
- 5 The skill of the operator is here called into play in not blocking movement of his boat by trying to force it against the obstruction and in quickly passing over the same as it is lowered.
- 10 The line 18 passes out of the tank and over a pulley 41 suspended from a spring 42, then over a pulley 43 and has its end secured to a drum 44 having secured to its upper face a clutch member 45. The drum 15 44 is loosely mounted on a vertical rod 46 upon the upper end of which is secured a manual operating wheel 47. Rod 46 may be of square cross section and slideable thereon is a clutch sleeve 48 which is supported in a bearing formed by a band 49 which is seated in an annular groove in the shank of sleeve 48 and is fastened to a bar 50 extending across the machine. Springs 51 normally hold bar 50 elevated so that sleeve 25 48 is out of mesh from member 45 and rod 46 may turn without effecting rotation of drum 44.
- Levers 52 are pivoted to the base, one being provided with a handle 53. Fingers 30 54 extend from levers 52 over bar 50 and a bar 55 is pivotally connected to levers 52. A spring 56 tends constantly to hold the members in the full-line position in Figure 1. In moving handle 53 to the dotted-line position, it is caught and retained by a spring finger 57 arranged in juxtaposition to an electric magnet 58 by means of which the lever 53 is released automatically as will be presently described.
- 40 A battery or other source of electrical energy is shown at 59 and has one terminal connected by a wire 60 with one of the binding posts of the magnet 58. A wire 61 leads from the other terminal of the battery a 45 plurality of signal lamps 62 there being one lamp 62 for each boat 14. A wire 63 connects each lamp 62 with one binding post of a respective switch 64, while the other binding post of each switch is connected by 50 a respective wire 65 with a trunk line 66 connected to the other binding post of the magnet. The blade 67 of the switch is carried by an arm of a lever 68 pivoted at 69 and connected by a link 70 with the upper 55 arm of a lever 71 the lower arm of which is adapted to be struck and operated by the respective boat 14. A spring 72 tends constantly to throw the blade 67 to inoperative position.

When the boat finishes its course, it strikes 60 and operates lever 71 which through link 70 and lever 68 closes switch 64, whereupon the respective signal 62 is lighted and the magnet 58 is energized to release 53 whereby clutch 48 is raised and the boat is returned by roller 16. 65

While we have described what is deemed to be the most desirable embodiment of our invention, it is obvious that many of the details may be varied without in any way 70 departing from the spirit of our invention, and we therefore do not limit ourselves to the exact details of construction herein set forth nor to anything less than the whole of my invention limited only by the ap- 75 pended claims.

What is claimed as new is:—

1. In a device of the class described, the combination of a tank, a boat mounted for movement in said tank, manual means for moving said boat in said tank, a slide bar mounted in said boat, manikins mounted on said slide bar, oars pivoted on said boat, operative connections between the manikins and said oars and means for automatically reciprocating said slide bar to cause said manikins to operate said oars upon operation of said manual means. 80
2. In a device of the class described, the combination of a tank, a boat mounted for movement in said tank, manual means for moving said boat in said tank, a slide bar mounted in said boat, manikins mounted on said slide bar, oars pivoted on said boat, operative connections between the manikins and said oars, means for automatically reciprocating said slide bar to cause said manikins to operate said oars upon operation of said manual means, and automatic means 85 for returning said boat to normal position. 90
3. In a device of the class described, the combination of a tank, a boat mounted for movement in said tank, manual means for moving said boat in said tank, a slide bar mounted in said boat, manikins mounted on said slide bar, oars pivoted on said boat, operative connections between the manikins and said oars, means for automatically reciprocating said slide bar to cause said manikins to operate said oars upon operation of 95 said manual means, and means for effecting a raising and dipping of the oars to simulate rowing. 100

In testimony whereof we have affixed our signatures.

RYUJI SATO.
CHIYOSABURO MATSUI.
